EMERGENCY GRATE

Robert C. Cross, Riverside, Ill., assignor to Sears, Roebuck and Co., Chicago, Ill., a corporation of New York

Application October 8, 1942, Serial No. 461,296

1 Claim. (Cl. 126—152)

This invention relates to emergency grates such as those employed in converting oil burners to use with coal or other solid fuel burners.

The term "furnace" is hereinafter used for convenience to denote heating plants generally, whether they be hot water or steam heating boilers or warm air furnaces.

It is an object of the invention to provide a conversion grate so constructed as to be usable in heaters or heating plants varying widely in furnace chamber sizes.

A further object is to provide a plurality of interchangeably interfitted grate parts whereby a grate may be assembled in various shapes and sizes and installed in any of a variety of furnace chamber shapes and sizes.

An additional object is to provide a conversion grate having frangible or severable portions enabling the grate to be reduced in size by breaking off sections to fit a selected size of furnace chamber.

Another object is to provide a conversion grate unit constructed to enable the fuel to be burned well beyond the fire bed area of the original oil burner element but instead more totally extensive with the walls of the furnace chamber.

Further objects and advantages of the invention will appear as the description proceeds.

The invention will be better understood upon reference to the following description and accompanying drawings in which:

Fig. 1 is a fragmentary vertical sectional view taken as indicated by the line 1—1 in Fig. 2.

Fig. 2 is a plan sectional view taken as indicated by the line 2—2 in Fig. 1.

Fig. 3 is a fragmentary plan view of separated complementary grate parts appearing in assembly in Fig. 2.

Fig. 4 is a vertical sectional view taken as indicated at 4—4 in Fig. 3 and showing how the complementary parts may be brought into assembly.

Fig. 5 is a sectional view taken as indicated at 5—5 in Fig. 3.

Fig. 6 is a sectional view similar to Fig. 5 but shows the parts assembled.

Fig. 7 is a fragmentary plan view similar to Fig. 2 but without the spacer or leaf, and with the parts reduced in area to fit a smaller furnace chamber.

Fig. 8 is an enlarged fragmentary sectional view taken as indicated by the line 8—8 in Fig. 7.

Fig. 9 is a fragmentary inverted plan view of the grate shown in Fig. 7.

Fig. 10 is an enlarged fragmentary sectional

view taken as indicated by the line 10—10 in Fig. 2.

Fig. 11 is a side elevation of the leaf inserted casting taken as indicated by the line 11—11 in Fig. 2.

Fig. 12 is a transverse sectional view showing a blower in an installation equipped with one embodiment of the invention.

Fig. 13 is an enlarged fragmentary end elevational view taken as indicated by the line 13—13 in Fig. 2, but with certain of the parts separated.

Fig. 14 is a view similar to Fig. 3 but of a modification.

Referring now more particularly to the drawings, the grate structure in accordance with my invention may comprise a pair of substantially semicircular members 15. Each member 15 may be of stepped, cascaded or terraced formation, comprising an upper central portion 16, and circumferential steps 18 of progressively increasing diameter downward, terminating at the outer periphery in a depending flange 19. The outer peripheries of the steps are selected in accordance with standard furnace chamber dimensions, the construction being such that, as will appear, the size may be readily reduced to the desired area by the user.

For the introduction of primary air to the fuel adapted to be burned over the grate, each grate member is provided with numerous openings. Said openings may be disposed in any desired location and arrangement, that disclosed here being illustrative. The openings 21 in the relatively horizontal portions of the steps are preferably arranged to provide at suitable intervals bridging portions 22 having score grooves or weakening notches 24, said notches being sufficiently deep and said portions being sufficiently short so that the user, with the aid of a chisel, can readily sever each portion thus weakened, and by repeating this operation at every such portion in the same circumferential series remove the portion outward of such series. This operation may be performed on each grate casting or forging, whereupon the members may be readily inserted into the user's furnace and assembled over the oil burner combustion chamber (Fig. 7).

The diametral margin of each member 15 comprises two portions 28 and 29, offset from each other, both vertically and horizontally, affording a recess 31 over the portion 28, said recess terminating inwardly at a wall 32 adjacent but short of the center of the member. The free edge 33 of said wall 32 may be flush with the free edge 35 of the depressed portion 28 and terminates on the

other side of the center a distance substantially equal to the distance of said recess 31 from the center, at a horizontally offset shoulder 38 forming the inner terminus of the undepressed marginal portion or lip 29. The free edge 39 of the lip 29 and the side wall 41 of the depression 31 are disposed on opposite sides of and equi-distant from the diametral plane containing the edges 33 and 35.

A hole 43 may be formed in one of the marginal portions, such as the portion 28, and a pin 45 formed in the lip 29. In assembling the members, they are disposed with their diametral margins crossed (Fig. 4) in such manner that each lip 29 overlies the depressed portion 28 of the companion member, with the pins 45 slightly entered or disposed to readily enter the cooperating holes 43. Then, as the members are relatively swung to lie flush with each other, the lip 29 of each comes to rest in the depression 31 of the other and the respective pins are fully entered in the respective holes, so that the members are locked together as a unit operative just as though they were cast in one piece, except for necessary clearance between pins and holes.

If desired, the pins 43 and holes 45 may be omitted, in which event the members may be placed on the support in the furnace and simply slid into assembly, the lip 29 of each member telescopically entering the depression 28 of the other until the members are in abutment as in Figs. 2 and 7.

Each member 15 may be provided with reinforcing ribs 46 reinforcing the various steps 18, and with additional ribs 47 reinforcing the top 16. The edge flange 19 serves the purpose among others, of preventing warp of the outer portion of the casting and affording edge reinforcement therefor in service.

The openings 21 serve not only to weaken the steps 18, but to admit air for combustion of the solid fuel supported by the grate. Additional openings 48 at the junctures of the steps 18 and openings 49 in the top 16 are provided to insure an adequate air supply.

Furnace retort openings and oil burner combustion chambers are conventionally round, ob-round, square or rectangular. The round grate just described may be suitable for any furnace wall and combustion chamber shapes.

For an elongated furnace, or one having an elongated combustion chamber, I may provide, in addition to the aforesaid semicircular members 15, interchangeable leaves or spacers 51 of generally rectangular form, each leaf being formed at each of its longitudinal margins with a lip 29 and a depression 31 in conformity with the aforesaid margins of the semicircular grate members 15, the margins being interchangeable. Thus if only one such spacer is used it can be assembled with each of the semi-circular members 15 in exactly the manner described above (Fig. 2). If two or more leaves are to be employed, it is obvious how they may be readily assembled with one another and with the semi-circular members 15.

It will be observed that, like the end members 15, the spacers 51 are formed with holes 21, 48 and 49 for admitting primary air supply and with frangible portions 53 adapted to form continuations of the series of such portions 22 in the members 15, so that the spacer peripheries may be broken off in conformity with the reduction in size of the end members 15, whereby the spacers in assembly with the end members may provide

a continuous periphery. The spacers may be provided with holes 43 and pins 45, or these may be omitted, as noted above in connection with the end members 15, and may be reinforced as by upper ribs 46 and a lower rib 55 suitably notched as at 57 to weaken the frangible portions 53 sufficiently to direct breakage when it is desired to reduce the size of the grate, while yet affording sufficient strength and resistance against accidental breakage.

Figure 1 shows how a conversion grate in accordance with my invention may be installed for use. To this end, I have shown a furnace combustion chamber 65 having a wall 66 and an oil burner combustion chamber 68 which is converted to use with solid fuel such as coal. Accordingly, the oil burner electrode-and-nozzle assembly are removed, and the oil pump and ignition wiring disconnected, leaving the air tube 69 equipped with a fan 71 for blowing primary air into the oil burner combustion chamber. Suitable heat insulation 72, such as rock wool or other material, is packed in the space between the furnace foundation wall or ash pit 66 and the oil burner combustion chamber, an annular sheet 74 of asbestos, metal, or other suitable material being applied to the top of the insulation and oil burner combustion chamber wall to provide a floor or support for the grate. If desired, the floor may be formed by a cement covering over the rock wool or other filler, and substantially flush with the top of the oil burner combustion chamber.

The parts of the grate, reduced to the desired size if necessary, that is, the maximum size to 35 which it can be reduced and still fit in a given furnace chamber, as explained above, are then inserted through the fire door or other suitable opening and assembled as explained above. The assembled grate unit is then adjusted so that 40 its periphery is substantially uniformly spaced from the interior wall 71 of the combustion chamber. Refractory cement or clay 78 is then applied at the periphery of the grate to seal its juncture with the floor 74, so that excess leakage 45 of primary air from the plenum space 79 beneath the grate will be precluded and at the same time the grate will be retained in the desired position. If the grate is not reduced, its depending peripheral flange 19 will rest on the floor 74 as shown 50 in Fig. 1. If the grate is of reduced size (Figs. 7 and 8), the outermost horizontal portion 83 of the grate may be spaced from the floor 74 by the depression 28 and pins 85, Fig. 9, formed on the bottoms of the steps, the bottoms of the pins being 55 in the same planes as the respective bottom surfaces of the depression 28 formed on the same member.

In use, solid fuel such as coal is fed onto the grate, and inasmuch as the grate has openings therethrough substantially to the outer periphery thereof, the primary air blown in by the fan will mushroom from the top of the oil burner combustion chamber, and reach all of the coal on the grate through said openings and thus all of the coal on the grate will be burned evenly. Accordingly, my invention affords in effect a plenum chamber extending a substantial distance laterally beyond the rim of the oil burner combustion chamber.

This is a substantial improvement over past 70 grates in this respect, such grates providing for the burning of only that portion of the coal which is directly over the oil burner combustion chamber.

The two end members being identical, and

therefore interchangeable, and the same being true for the spacers, and in view of the formation of the parts which adapts them to form units to fit various sizes of furnace walls, it is apparent that I have provided a conversion grate construction of extremely low cost which makes it a simple and inexpensive matter in a time of economic shortage, to convert oil burners to solid fuel burners.

For reconversion to oil burning, it is an easy matter to remove the refractory, separate and remove the grate parts and reinstall the oil burner apparatus.

Various modifications coming within the spirit of my invention may suggest themselves to those skilled in the art, and hence I do not wish to be limited to the specific form shown or uses mentioned, except to the extent indicated in the appended claim, which is to be interpreted as broadly as the state of the art will permit.

I claim:

5 A solid fuel conversion grate, comprising a pair of semi-circular castings, each having two edge formations oppositely offset from a diametral line constituting a median junction between said castings and meeting at a midpoint of said line, one of said edge formations of each casting being throughout recessed to receive the non-recessed edge formation of the other of said castings during interfitting placement of said castings one with the other, a series of cascaded semi-circular sections integral with each of said castings having progressively larger diameters and progressively lower planes in horizontal correspondence, said edge formations defining said cascaded sections, 10 and an optionally insertible intermediate casting having edge formations complementary to those of its adjacent semi-circular casting and correspondingly offset so as to afford elongation to said conversion grate in a direction transverse 15 of said diametral line.

ROBERT C. CROSS.
